UNITED STATES PATENT OFFICE.

ALFRED HENRY GREBE, OF HOLLIS, NEW YORK.

UNIT-CONTROL SYSTEM FOR ELECTRIC CIRCUITS.

Application filed May 13, 1925. Serial No. 30,033.

My invention relates particularly to a system of unit control for simultaneously adjusting the variable members of a plurality of circuit elements.

5 Broadly considered, such systems are well known in the art but their use has not become general, owing mainly to the fact that the various circuits of a series do not ordinarily respond alike to the same adjustment of their tuning elements and, in order to bring them to resonance, individual adjustment of the several circuits is usually required.

As far as is known, the prior art unit control systems consisted of means connecting the variable members of the tuning elements of a series of circuits, either permanently or at will, by means of a suitable control and, in the latter case, the members 20 had to be either all connected for simultaneous adjustment or all disconnected for individual adjustment, no variation or flexibility being permitted.

The main object of the present invention 25 is to render the control system "flexible"— that is to say, to provide control, by means of which two or more or all of the tuning elements of a series of circuits may be connected at will, for simultaneous adjustment; further, to so connect the elements as to create lost motion of predetermined value, which will permit limited individual adjustment of any one of the elements and finally, to make it possible to readily and 30 conveniently release all of the elements for unlimited individual adjustment or connect them all up for simultaneous adjustment under unit control.

A construction suitable for carrying my 40 invention into effect is illustrated in the accompanying drawings, but I do not wish to be understood as limiting myself to the same, as various changes may be made therein or other forms employed without departing from the spirit and scope of the 45 present invention.

In the drawings—

Fig. 1, is a view in front elevation of a 50 well-known type of radio receiving set, to which my invention is shown applied;

Fig. 2, is a plan view thereof, with a portion of the hinged top cover of the cabinet broken away;

Fig. 3, is an enlarged view of the main 55 dials of the tuning elements of the receiving set, showing optional coupling for giv-

ing "unit control" of two or more of the elements;

Fig. 4, is a sectional view, on an enlarged scale, of a detail of the coupling, and

Fig. 5, is a view in elevation, partly in section, taken on the line s^5, s^6 , of Fig. 4.

Referring now to the drawings, for convenience of illustration, I have shown my invention applied to a radio set, in common use, known as the "synchrophase" receiver, which employs three variable condensers 1, 2 and 3, as the tuning elements.

As the construction, operation and adjustment of these condensers is well known in the art, it will not be necessary to describe them in detail. They are provided, in the usual manner, with scaled dials $1^a, 2^a$ and 3^a , fast on the shafts $1^b, 2^b$ and 3^b of the rotor members and by means of which such members may be adjusted by manipulating the dials, which project through slot-like openings in the front panel of the cabinet.

In this particular receiver, the relative arrangement of the three tuning condensers lends itself very conveniently to the application of my improved unit control system, which consists, in the present embodiment of the invention, of a chain and pulley connection between the condensers, for transmitting motion imparted to any one of the three, to the other two, so that they move simultaneously and to the same extent, excepting an intentional provision in the connection for lost motion of predetermined value, the purpose of which will be later on explained.

As shown, the condenser 1, has mounted on an extension of its shaft 1^b , a grooved pulley 1^c , which, by means of a friction clutch, shown in the form of a butterfly nut 1^d , threaded on the end of the condenser shaft, may be clamped to turn with the shaft or run as an idler.

Fast on the shaft of the condenser 2, there is a double groove pulley 2^c , which is connected with the pulley of condenser 1, by an endless chain 4.

The full range of adjustment of the condensers requires only a half turn of the shafts, and this permits the chain 4 to be secured to the pulleys $1^c, 2^c$, at points $1^e, 2^e$, the effect of which is to avoid wasteful loss in transmission of motion from one condenser to another.

A connection similar to that above described, is provided between the condensers

2 and 3, by means of the chain 5, pulley 3^c and nut 3^d, the chain being secured to the pulleys at points 2^c and 3^c.

In the operation of this particular set, the adjustment of the moveable members of the several tuning condensers is found to be substantially the same for any wave length, that is to say, ordinarily, there is not more than two or three scale divisions difference on the dials, so that it is practicable, in connecting the three tuning condensers of this receiver for simultaneous adjustment, to provide for this slight difference in the dial settings, by creating lost motion, of predetermined value, in the chain connections between the dials, which will permit limited individual adjustment of any one of the condensers to the extent required.

A simple and effective way of providing the required lost motion is to employ chain belts of definite over-size and in taking up the resulting slack, any one of the dials may be rotated in either direction, a distance equal to three or four dial scale divisions, before motion from the dial being rotated, will be transmitted to the other dials.

From the foregoing, it will be seen that when all of the tuning condensers are to be operated by unit control, it is only necessary to tighten the two butterfly nuts 1^a, 3^a, and, using any one of the dials as a driver, motion given it will be transmitted simultaneously, and in the same direction, to the other condenser dials of the series. If, on the other hand, it is desired to render the unit control system wholly ineffective, to permit unlimited individual adjustment of each of the condenser dials, this is accomplished by loosening the nuts 1^a, 3^a.

If, as frequently happens, the operator prefers to put the condensers 2 and 3 under unit control and leave the condenser 1, free for unlimited adjustment, it is only necessary to loosen the nut 1^a and tighten the nut 3^a. Thus arranged, the operator will also have the additional advantage of limited individual adjustment of either of the condensers 2 and 3, through the lost motion provided in the chain belt.

It will be understood that the invention may be applied to control variable inductances and other electrical elements, as well as condensers, which are here shown, as above stated, merely for convenience of illustration.

It will also be understood that the application of the invention need not be directly to the dials or to the face of the dials but may be otherwise arranged, according to the relation and grouping of the circuit elements.

The type of chain belt may be departed from and other forms of friction clutch employed according to preference, such details being usually determined by the market price of the set. 65

Having, therefore, described my invention, I claim:—

1. In a unit control system for simultaneously adjusting the variable members of a plurality of circuit elements, the combination of a plurality of variable members and means connecting said variable members for imparting simultaneous movement to said variable members, said means being constructed to provide lost motion between the elements for the purpose of permitting individual adjustment of each of said variable elements. 75

2. A control for a plurality of variable circuit elements comprising a plurality of individually adjustable variable circuit elements, a lost motion connection between said elements, said lost motion connection being arranged to impart simultaneous movement 85 to said elements while permitting limited individual adjustment of each of said elements. 85

3. In a unit control system for simultaneously adjusting the variable members of a plurality of variable circuit elements, a connection between said elements for imparting simultaneous movement thereto, said connection between the elements being such as to create lost motion of predetermined 95 value permitting limited individual adjustment of the elements, and means for releasing the elements for unlimited individual adjustment. 95

4. In a tuning system the combination of a central tuning element and corresponding tuning elements located on opposite sides thereof, a rotatable shaft for controlling each of said tuning elements; a pulley member located on each of said rotatable shafts, flexible chain connectors extending between the pulley member on said central tuning element and the pulley members on each of said corresponding tuning elements, said flexible chain connectors being slackened between said pulley members for introducing lost motion between said tuning elements for permitting limited individual adjustment of any one of said tuning elements, said pulley members on each of said corresponding tuning elements being arranged to be locked or released from direct rotation with respect to the rotatable shaft thereof whereby simultaneous or unlimited individual adjustment of any one of said tuning elements may be effected. 110 120

ALFRED HENRY GREBE.
